HELICOPTER

Ernest Stuckal, Stratford, and Lewis G. Knapp and Edward F. Katzenberger, Westport, Conn., assignors to United Aircraft Corporation, East Hartford, Conn., a corporation of Delaware

Filed June 4, 1963, Ser. No. 75,215

Term of patent 14 years

(Cl. D71—1)

FIG. 4

FIG. 1 is a side elevational view of a helicopter, showing our new design;

FIG. 2 is a front elevational view thereof;

FIG. 3 is a rear elevational view thereof; and

FIG. 4 is a top plan view thereof.

The fragmentary showing of the rotor blades is for convenience of illustration. The dominant features of our design reside in the portions shown in full lines.

We claim:
The ornamental design for a helicopter, substantially as shown and described.
